(57) **CLAIM**

The ornamental design for a toy brick with a vertical shaft as shown and described.

DESCRIPTION

FIG. 1 is a top perspective view of a toy brick with a vertical shaft.

FIG. 2 is a front plan view of the toy brick with a vertical shaft.

FIG. 3 is a back plan view of the toy brick with a vertical shaft.

FIG. 4 is a side plan view of the toy brick with a vertical shaft.

FIG. 5 is a top plan view of the toy brick with a vertical shaft.

FIG. 6 is a bottom plan view of the toy brick with a vertical shaft; and,

FIG. 7 is a bottom perspective view of the toy brick with a vertical shaft.

The broken lines in the figures show features of the toy brick with a vertical shaft that form no part of the claimed design.

1 Claim, 7 Drawing Sheets
